UNITED STATES PATENT OFFICE.

EDWARD R. WILSON AND PERCY H. BEST, OF BRIDGEPORT, CONNECTICUT.

TOY SUBMARINE.

1,427,669.

Specification of Letters Patent. Patented Aug. 29, 1922.

Application filed June 29, 1921. Serial No. 481,264.

To all whom it may concern:

Be it known that we, EDWARD R. WILSON and PERCY H. BEST, citizens of the United States, and residents of Bridgeport, in the 5 county of Fairfield and State of Connecticut, have invented certain new and useful Improvements in Toy Submarines, of which the following is a specification.

This invention relates to a novel amusement device and has more especial reference to water toys adapted to be propelled on and beneath the surface of the water and designed in imitation of any desired object as for instance, submarine boats, fish, ducks, 15 etc.

A feature of the invention is to provide a submersible object of the present character which, while of the simplest and most economical construction, will be reliable for an 20 indefinite period of times in ideally performing its intended function as will fully hereinafter appear.

A further and more specific object is to provide a toy which can be carried out in 25 a practical way in the form of a submarine boat and be equipped with simple means for automatically shifting the center of gravity of said boat to and from a normal position to alternately maintain the same in horizontal- 30 tal and oblique positions, and with driving means for propelling the boat forwardly in a plane which approximately coincides with the longitudinal axis of said boat, whereby, when horizontally positioned, the boat will 35 be propelled in a plane which is parallel with the surface of the body of water in which the boat is situated, and, when obliquely positioned, will be driven to or toward the bottom of said body of water. To

40 this end we provide a toy boat which preferably has a displacement capacity sufficient to maintain it but partially submerged, so that when said boat has returned to its normal, horizontal position and is completely 45 submerged a greater or less distance, it will immediately return to its natural, partially submerged position, whence, when said submarine is again shifted to oblique position, it will again be driven downwardly in the 50 body of water to repeat the cycle just described, and we provide within the body or hull of said toy submarine boat, a longitudinally movable weight which is normally located to give said submarine an even keel, 55 but which is arranged to be at intervals

moved longitudinally forward in said body or hull by means of a clock spring movement or other motor constituting the driving mechanism of a boat, and thence released to return to its normal position, some 60 suitable means, such as a coil spring, being utilized to immediately return said weight to that position it must occupy within the body or hull to establish an even keel, as soon as released from said clock spring 65 movement, and a segment associated with said clock spring movement and a rack associated with said movable weight, preferably constituting the simple means for imparting said longitudinal forward move- 70 ment to said weight.

With the above and other objects in view, the invention will now be fully described, it being understood that such changes in details of construction and arrangement of 75 parts may be made as fall within the spirit of the invention and within the scope of the appended claims.

In the accompanying drawing forming a 80 part of this specification,

Fig. 1 is a longitudinal sectional view through the center of the toy submarine boat, showing the same as when horizontally positioned;

Fig. 2 is a transverse sectional view on 85 line 2-2 of Fig. 1, looking in the direction of the arrows; and

Fig. 3 is a view corresponding with the 90 showing of Fig. 1, but showing the contrivance in an oblique position.

Supported from the body or hull 10 of the boat, as by means of brackets 11 is a clock spring movement 12, including a winding stem 13 positioned beneath a key opening 14 for which there is a closure cap 15, and a 95 driving shaft 16 of ordinary or preferred construction, adapted to the purpose of rotating the propeller shaft 17 carrying the propeller 18 which is preferably set to drive the boat in a plane approximately coinciding with the longitudinal axis thereof. The outer surface of the hull may be equipped with fins 19 and the hull may have therein lead or other suitable ballasts 20. The parts and arrangement of parts so far described 100 are common in toy boats and need no further description.

A suitable way 21, located upon the hull and extending longitudinally thereof, receives a longitudinally movable weight 22 110

including a rack 23. A coil spring 24 having one of its ends attached to the rack 23 and its other end attached to the boat hull, holds the weight and rack in normal position 5 against the stop pin 24^a, that is, in the position the weight occupies in the body to establish an even keel. Rollers 25, best shown in Fig. 2, mounted upon said rack, are adapted to ride upon tracks 26, constituting 10 inturned flanges of the way 21, to hold the weight 22 away from the bottom of said way 21 to thus reduce friction as said weight is moved longitudinally forward in said boat and returned to its normal position in the 15 manner now to be fully set forth.

A segment 27 which is mounted within the clock spring movement in the manner shown, or in any other preferred manner, has teeth 28 which desirably extend over an arc of 20 about 180°, and the teeth 28 of said segment are designed to mesh with the teeth of the rack 23, said rack and segment preferably having a corresponding number of teeth.

The manner in which the boat operates 25 will be obvious. The segment 27 rotates continuously forward, in clockwise direction as shown by the arrow in the drawing, to be in engagement for one-half of each of its revolutions with the teeth of the rack 23, 30 with the result that the rack and its weight are moved longitudinally forward from the normal position in which shown in Fig. 1 of the drawing to that in which shown in Fig. 3 thereof. Evidently, as the segment rotates 35 further forwardly, the last tooth thereof is removed from the last tooth of the rack, and the spring returns the weight to its position against the stop pin. The movement of the weight forwardly shifts the center of 40 gravity of the boat to tilt the same to an oblique position, and the propeller 18, set to drive the boat in a plane which approximately coincides with the longitudinal axis thereof, causes the same to move to or toward 45 the bottom of the body of water in which the boat is situated. As soon as the segment has released the ratchet and the weight has returned to normal position under the action of the coil spring 24, the boat 50 establishes an even keel, and as the motive force is now working in a plane which is parallel with the level of the water, and not obliquely downward therefrom as when the boat is tilted, and the displacement capacity is only sufficient to maintain the toy 55 submarine boat partially submerged, the buoyancy of said boat will return it to about that position disclosed in Fig. 1, whence, as soon as again shifted to oblique position, it

will again be forced downwardly in the 60 water.

While we have shown and described our invention as applied to a toy submarine boat, yet it will be understood that it may be contained within and used for operating other 65 forms of water toys such for instance as fish or birds.

Having thus fully described the invention, what we claim as new and desire to secure by Letters Patent is:

1. In a submarine boat, driving mechanism set to propel said boat in a plane approximately coinciding with the longitudinal horizontal plane of the boat, and means for shifting the center of gravity of said 75 boat to alternately maintain the same in horizontal and oblique positions, a spring motor mounted in a frame secured to the boat and including a segment of a gear, a guide-way secured to the lower portion of 80 the motor frame, a weight and rack slidable in said guide-way and adapted to be engaged by the segment and moved longitudinally of the boat to tilt the same, and a spring for returning the weight and rack 85 when disengaged by the segment, whereby the boat will level itself to be driven directly forward and at the same time rise in said body of water.

2. In a submarine boat, driving mechanism set to propel said boat in a plane approximately coinciding with the longitudinal horizontal plane of the boat, and means for shifting the center of gravity of said boat to alternately maintain the same in 90 horizontal and oblique positions, a spring movement including a frame, a gear and a segment of a gear, mounted in the frame, a longitudinal guide-way positioned beneath the movement and forming an integral part 95 of the frame, a rack slidable in said guide-way and adapted to be engaged by the segment for movement in one direction, and a spring one part of which is connected to a fixed member and the other part to the rack 100 to move the same in an opposite direction, whereby the boat will level itself to be driven directly forward and at the same time rise 105 in said body of water.

Signed at Bridgeport, in the county of 110 Fairfield and State of Connecticut this 27th day of June, A. D. 1921.

EDWARD R. WILSON.
PERCY H. BEST.
